UNITED STATES PATENT OFFICE

ELMER H. GROVES, OF MINNEAPOLIS, MINNESOTA

INFANT'S GARMENT

Application filed September 17, 1929. Serial No. 393,193.

This invention relates to garments and more particularly to an article of this character which is especially adapted for infants or very small children and has for one of its objects to provide, in a manner as hereinafter set forth, a garment of this character, having means thereon for expeditiously and securely connecting a restraining strap or a plurality of straps thereto for the purpose of retaining the infant in a chair, bed, or any other desired place.

Another object of the invention is to provide, in a manner as hereinafter set forth, a garment of the above mentioned character having means embodied therein for adjusting the same in a manner to adapt the garment to infants or children of different sizes.

Other objects of the invention are to provide an infant's garment of the aforementioned character, which will be simple in construction, strong, durable, efficient in its use, and which may be manufactured at low cost.

Other objects and advantages of the invention will become apparent from a study of the following specification taken in connection with the accompanying drawings, wherein like characters of reference designate corresponding parts throughout the several views, and wherein:

Figure 1 is a front elevation of a garment constructed in accordance with this invention.

Figure 2 is a rear elevation thereof.

Figure 3 is a side elevation of the garment.

Referring to the drawings in detail, the reference character 1 designates generally a body or waist portion having a front side 2, a rear side 3, and connecting side portions 4. The body portion 1 is provided with arm openings 5 and the neck opening 6 in its upper end. The front 2 and back 3 of the garment are provided at their upper ends with pairs of spaced co-acting overlapping shoulder straps 7 and 8. The front straps 7 are each provided with a button 9 on their outer faces and adjacent their free ends. A button 10 is also secured on the outer face of each of the front straps 7 adjacent the point where said straps join the body portion 1 and in spaced relation to the buttons 9. The rear

straps 8 are each provided with a series of button holes 11 adjacent their points of connection with the body portion 1 for the reception of the buttons 9 of the straps 7 and with another series of button holes 12 for the reception of the buttons 10 of the straps 7.

As most clearly illustrated in Figure 3 of the drawings, the rear strap 8 overlaps the front strap 7 and said straps are adjustably connected together by selectively engaging the buttons 9 and 10 in the button holes of the series 11 and 12, respectively, as will be obvious.

Secured to the body 1 are a plurality of circumferentially spaced connecting rings 13, which are mounted in eyelets 14, said eyelets 14 being anchored in flexible pieces of material 15 which are stitched to the body portion 1. For the purpose of adjusting the body portion of the garment, a pair of co-acting flexible straps or tabs 16 are stitched at their opposite ends thereto on the back 3 and are adjustably connected together through the medium of the buckle 17.

It will thus be seen that I have provided a garment for infants having means thereon for attaching a restraining strap at the most desirable points. Should it be desired to prevent the infant from leaning forward and possibly falling out, while seated in a chair, the anchoring strap (not shown) would be secured to the rear ring 13 and have its opposite end anchored to the back of the chair and for the purpose of preventing the infant from falling out of bed, a strap (not shown) may be coupled to each of the side rings and the opposite ends thereof secured to opposite sides of the bed.

It is to be understood that the garment may be constructed of any suitable material. It will also be seen that I have provided novel and durable shoulder strap adjusting means.

It is believed that the many advantages of a garment constructed in accordance with the present invention will be readily understood and although the preferred embodiment of the invention is as illustrated and described, it is to be understood that changes in the details of construction may be had,

which will fall within the scope of the invention as claimed.

What is claimed is:

A garment of the character described comprising a tubular body encircling portion formed of a single piece of material, a series of flexible sheets stitched to the body portion in circumferentially spaced relation, an eyelet mounted on each sheet and projecting outwardly therefrom, a metallic coupling ring loosely mounted for swinging movement on each eyelet, and means extending circumferentially on the rear of the body encircling portion for adjusting said portion.

15 In testimony whereof I affix my signature.

ELMER H. GROVES.
